UNITED STATES PATENT OFFICE.

JACOB S. AYDELOTT, OF XENIA, INDIANA.

LOCK.

SPECIFICATION forming part of Letters Patent No. 281,822, dated July 24, 1883.

Application filed February 16, 1883. (Model.)

To all whom it may concern:

Be it known that I, JACOB S. AYDELOTT, a citizen of the United States, residing at Xenia, in the county of Miami and State of Indiana, have invented certain new and useful Improvements in Burglar-Proof Locks, of which the following is a specification, reference being had therein to the accompanying drawings.

10 My invention relates to an improvement in burglar-proof locks; and it consists, first, in the combination of the frame having a suitable slot, that is notched at each of its ends upon its inner side, a pivoted plate which covers the key-hole, and a suitable locking device for locking the plate in position; second, in the combination of the pivoted plate for closing the key-hole, and which is provided with a locking device, a frame provided with 15 a slot having a notch at each end, and the latch-bolt provided with a shoulder behind which the end of the plate is made to catch, as will be more fully described hereinafter.

The object of my invention is to provide a 20 burglar-proof lock in which there is a plate for covering the key-hole, so that no key or other device can be inserted from the outside, and in which both the knob-bolt and the locking-bolt are locked in position.

25 Figure 1 is a side elevation of my invention complete. Fig. 2 is a side view of the key alone.

A represents the frame of the lock, which has a curved slot, B, made through that side 30 which comes next to the room in which it is placed. This slot has a suitable recess or notch, C, formed at each of its ends for the locking-catch to catch in. Pivoted in the lower part of the frame, at D, is the plate E, which 35 serves the twofold purpose of closing the key-hole from the inner side of the frame, so that no key or other tool can be inserted from the outside, and of locking the bolt F in position, so that it cannot be operated by the knob.

40 In order to hold this locking-plate in position at either end of the slot B, it is provided with a small knob or handle, a, which projects through the slot, and with a suitable spring catch or bolt, c, which catches in the knob at 45 either end of the slot. When this plate is

raised in an upright position, it closes the key-hole and locks the bolt F by catching against a shoulder formed on its under side. When this plate is turned backward, as shown in dotted lines, the key-hole is left exposed 55 and the bolt F is unlocked, so that the bolt can be freely operated by the knob. This bolt F has the follower H placed in an opening, U, that is made through its inner end, and the bolt is automatically returned to place, 60 after having been moved by the knob, by means of a spring, I, which bears against its rear end. This spring I extends forward just under the key-hole, and has fastened to its front end a connecting-rod, K, which has its 65 lower end pivoted to the locking device L. This locking device is pivoted upon the same pivot as the locking-plate, and also has a suitable spring, N, placed under its front end, which is provided with a projection, O, for 70 catching in the recesses P, formed in the lower edge of the locking-bolt Q. While this projection catches in one of the recesses in the lower edge of the locking-bolt, which it will do automatically whenever the bolt is moved 75 forward or back by the key, the bolt is locked in place, so that it cannot be moved by any other key than the one which was designed for the lock. The key shown in Fig. 2 is provided with two prongs, R, which straddle over 80 the spring as the key is inserted and turned around, and the part S, which comes between these two prongs, acts as a cam to press the spring down. When the spring is pressed down, the locking device is forced downward 85 by the connecting-rod, so as to leave the bolt free to move, and then the part R catches against the small projections T upon the top of the recessed portion of the bolt and moves the bolt either forward or back.

90 The great advantage of this lock consists in being provided with a device which not only closes the key-hole, but also locks the knob-bolt, so that, even if the key should be lost, the door will be securely locked and the key-hole guarded, so that no key or other device can be inserted into the lock for the purpose of picking it.

Having thus described my invention, I claim—

1. The combination, with the frame provided with a slot having a notch at each end, of the pivoted locking-plate that is provided with a catch for catching in either of the notches and locking the plate in position over the key-hole, substantially as described.

2. In a lock, a pivoted plate for closing the key-hole, and provided with a locking device, a, a frame provided with a slot having a notch, C, at each end, and the latch-bolt F, provided

with a shoulder, behind which the end of the plate is made to catch, substantially as shown and described.

In testimony whereof I affix my signature in presence of two witnesses.

JACOB S. AYDELOTT.
